United States Patent Office

Des. 179,954
Patented Mar. 26, 1957

179,954

SMOKING STAND

Logan B. Schirmer, Monrovia, Calif., assignor to National Novelty Inc., Santa Ana, Calif., a corporation of California

Application June 13, 1955, Serial No. 36,495

Term of patent 14 years

(Cl. D85—2)

Fig. 1.

Fig. 2.

Fig. 3.

Fig. 1 is a top plan view of a smoking stand showing my new design;

Fig. 2 is a side elevational view thereof partly in cross section; and

Fig. 3 is a cross-sectional view thereof, taken on line 3—3 of Fig. 2.

I claim:

The ornamental design for a smoking stand, as shown.
